UNITED STATES PATENT OFFICE.

THOMAS FARMER, JR., OF NEW YORK, N. Y., ASSIGNEE TO CONSOLIDATED CAR-HEATING COMPANY, OF ALBANY, NEW YORK, A CORPORATION OF WEST VIRGINIA.

DOOR-MOTOR.

1,281,543.

Specification of Letters Patent. Patented Oct. 15, 1918.

Application filed July 17, 1915. Serial No. 40,378.

To all whom it may concern:

Be it known that I, THOMAS FARMER, Jr., a citizen of the United States, residing at New York city, borough of Manhattan, county and State of New York, have invented certain new and useful Improvements in Door-Motors, the following being a full, clear, and exact disclosure of the one form of my invention which I at present deem preferable.

For a detailed description of the present form of my invention, reference may be had to the following specification and to the accompanying drawings, which illustrate my invention, wherein—

Figure 1 shows my motor applied to a door;
Fig. 2 a plan view thereof on a larger scale;
Fig. 3 is a front elevation thereof;
Fig. 4 is a rear end view and
Fig. 5 is a diagram of the electrical connections.

My invention relates to the mechanical operation of a door by means of a pneumatic motor electrically controlled. In particular, I provide a magnet for controlling the inlet and exhaust valves of each of the two cylinders of the motor and a push button for closing the circuit of each magnet. In addition, I arrange that the magnet circuit, after being closed by the push button, shall be retained closed by the action of the motor itself until after the motor stroke is completed or nearly so, when the magnet circuit is automatically broken. This arrangement is duplicated for each cylinder of the motor.

Referring to the drawing, A and B represent two air cylinders, one being a duplicate of the other, and the two being employed for the opening and closing movements of the door respectively. The pistons of the two cylinders are connected by a rack bar C which intermeshes with a sector D on a lever that operates the door. Such an arrangement is well known and calls for no further description. The lever itself is of a telescoping construction. It is composed of a flat box-like section E, in which slides one end of a connecting rod F which is provided at its outer end with a short spindle f by which it may be jointed to the door or to a second lever that is connected to the

door. Any desirable form of connection 55 between the door and the rod F may be employed, but for illustration I have shown the rods as jointed to a sleeve G free to slide on a guide rod g secured to one edge of the door H, as appears in Fig. 1. When 60 the door is closed the rod F will be in its horizontal position, as shown in that figure. The rod F, where it enters the box-section E, is provided with a slot f¹ through which passes a pin f² to retain it in the section 65 E. The rear end of rod F rests against springs J J which tend to force the rod outwardly and thereby extend the telescoping door-operating lever. When, however, 70 the door is closed and the rod F is in its horizontal position at right angles to the door, as in Fig. 1, the door can be opened by hand to a certain extent owing to the yielding of the springs J J. When, however, 75 the door is open, or is being moved from open to closed position, or vice versa, the angular relation of the rod F to the door will cause a side pressure of the rod against the box-section E that will prevent the rod from being pushed into the section E against 80 the pressure of the springs J J. By this means the danger of a person's hand or arm being injured by being caught in the door is averted, the strength of the springs J J not being sufficient to cause injury. At the 85 same time, if a lady's dress or other article, be caught in the door it can readily be released by opening the door a short distance against the pressure of the springs.

The box-section E is pivoted to the cylinder casting by means of a pin I, which is passed through the bearings K K¹ formed on the cylinder casting and through the said box-section E and retained by a split pin i. The box-section E is preferably cast 90 in one piece with an extension E¹ on its rear side which is, in turn, integral with the toothed sector D which is engaged by the rack C and is, moreover, provided with an angular plate E² which extends parallel with the box-section E and is concentric with the bearings K K¹. To the aforesaid part E² is attached a drum L of insulating material carrying contact plates 1 and 2, 95 also a short contact plate 3 and a longer contact plate 4 upon which suitable contact fingers are arranged to bear, as will be hereinafter described.

At the rear end of the cylinder B is formed a hollow casting B¹ which contains the inlet and exhaust valves of the cylinder B, together with the operating magnet 5 therefor. A similar hollow casting A¹ is provided for cylinder A to contain the valves and operating magnet of that cylinder.

Turning to Fig. 5, the operating magnet 10 for the valves of cylinder B are shown at 20, the armature 21 of the magnet being provided with a stem 22 of non-magnetic material which passes down through a chamber 23 and is there provided with a valve 24 15 designed to coöperate with a valve seat in a partition which separates the said chamber 23 from a chamber 25 which leads to the rear end of the cylinder B. The chamber 23 is provided with an exhaust duct 26 in communication with the atmosphere. The stem 22 also carries a second valve 27 that co-operates with a valve seat in a partition which separates chamber 25 from a chamber 28 that communicates with the source of air 25 supply. A spring 29 tends to hold the valves 24 and 27 in the position shown in Fig. 5, wherein the cylinder B is open to the exhaust 26 by way of the chamber 25 and the opened valve 24, the admission valve 27 being now closed. When, however, the magnet 20 is energized the conditions will be reversed, the valve 24 being closed, thereby shutting off the exhaust, and the valve 27 30 being opened, thereby admitting air to the cylinder.

The insulating drum L, which, as before described, is set concentrically with the sector D and the box-section E so as to rotate therewith, is shown in Fig. 5 with its contact plates developed in a plane. The contact spring or finger 5 bears constantly on the metallic plate 1 of the drum L and a similar spring or finger 6 bears constantly on the similar metallic plate 2. The inner edge of plate 1 is provided with a vertical cam-flange 12 and the plate 2 is provided with a similar cam flange 13. These flanges are to be engaged by a contact roller 9 pivoted on the stationary plate 10 and provided with a spring 11 to throw the roller to one side or the other of its dead center whenever that roller is forced over to one side or the other by the cam-flange 12 or the cam-flange 13. T represents a battery and B³—B⁸ represent push buttons, which, when pushed will close circuits from the battery T through the wires 30 and 31 to the respective magnets 20 and thence to ground. When either magnet 20 is energized the exhaust 45 valve 24 of its casing is closed and the admission valve of said casing is opened. Referring to Fig. 5, assuming that the right hand switch B³ is moved to the dotted line position to close the circuit, the magnet 20 50 will be energized to close valve 24 and open

valve 27 whereupon the air will enter behind the pistons of the cylinder B and through the rack C and sector D, will start to operate the door. At the same time it will start the drum L to rotating in the direction indicated by the arrow 40 whereupon the roller 9, which is shown in the figure as being held by the spring 11 on the lower side of its dead center, will come into engagement with the flange 13 on plate 2 and establish electrical connection therewith. That will close a second, retaining circuit through the magnet 20 independent of the one heretofore traced which contains the push button B³. This retaining circuit is from battery 80 T by the wire 50 to the plate 10 and roller 9, thence to the plate 2 and the contact spring 6, to the wire 51 which leads, by the wire 31, to the magnet 20 and thence to ground. This circuit will be maintained 85 until the piston reaches the end of its stroke, it being remembered that the movement of the piston, inaugurated by controlling valve B', causes a simultaneous movement of the drum L in the direction of the arrow 4 of 90 Fig. 5. Thus, during the stroke of the piston, the roller 9 will travel along flange 13 of plate 2—or more exactly, the flange 13 will travel along roller 9—until near the end of said stroke the roller will encounter 95 the curved part of said flange 13 (which is shown in Fig. 5 at the left hand end of the flange) and will thereby be thrown across its dead center line. That will cause the roller to part from flange 13 with a snap 100 and so break the maintaining circuit aforesaid. The parts will then remain at rest, the roller 9 standing in a position to engage the opposite flange 12 on the plate 1 whenever the piston starts on its return stroke. 105 The return stroke will be inaugurated by closure of the left hand switch B³ which will control the magnet of valve A' and admit air to cylinder A precisely as the right hand switch B³ controlled the magnet of valve 110 B' and admitted air to cylinder B as heretofore described. It will be understood that the admission of air pressure to one cylinder coincides with the opening of the exhaust of the other cylinder. The said return 115 stroke, under the force of cylinder A, will cause a reverse movement of drum L in a direction opposite to said arrow 40 and the roller 9 will first engage the left hand end of flange 12 and travel along that flange 120 during the said return stroke. Near the end of the stroke the roller will encounter the curved part of flange 12 (at the right hand end of the flange in Fig. 5) and be thereby deflected downward until it snaps back 125 across its dead-center line to the position shown in said Fig. 5. In thus traversing flange 12 the roller will maintain a retaining circuit for the magnet of valve A' exactly as it maintained the retaining circuit for the 130

magnet of valve B' while traversing flange 13. In like manner it will break the retaining circuit with a snap when it reaches the curved end of the flange and is thereby thrown across its dead center line. The action in one direction is a duplicate of the action in the opposite direction, being started by manually closing one of the valve-magnets; that being followed by the starting of the door and the closure by roller 9 of a retaining circuit for the corresponding magnet, which circuit is automatically broken with a snap at the end of the run of the door, the parts being left in position ready for the return run whenever the other switch B³ is closed. It will, therefore, be possible to start the door into operation by merely closing the push button B³ for a brief period sufficient to start the motor and close the retaining circuit by contact of the roller 9 and the plate 2. The push button may then be released but the motor will continue to operate to the end of its stroke. In Fig. 5 the arrows applied to the casing A' and B' indicate that the casing B' is exhausting from the cylinder B at the same time that the motive fluid is flowing to the cylinder A. Said figure illustrates all of the parts in the positions which they have reached at the end of the last operation of the device by which the door was operated through supplying power to cylinder A. It is to be understood that as each cylinder received the motive fluid the other cylinder exhausts. If desired, a normally-closed push-button X may be located in wire 50 for stopping the door in case of emergency, but ordinarily the door will be permitted to make its complete run before the air is cut off from its motor and its exhaust opened. The arrangement for cylinder A is identical with the one just described for cylinder B. It should be observed that plates 1 and 2 are both secured to the drum L by screws which pass through slots in the plates. By this means the plates can be adjusted in position on the drum and the time at which the retaining circuit will be broken thereby adjusted correspondingly.

The drum L also carries a short contact plate 3 which in the normal position of the drum, the door being then closed, bridges between contact fingers 7 and 14 to close the usual signal circuit which notifies the motor-man that all the doors on the train have been shut. Whenever the door is open this circuit is broken at the contact fingers 7 and 14. It is not necessary to describe this signal circuit further, since it is one well known in the art. On the other hand, the contact plate 4 on drum L acts to bridge between the fingers 8 and 16 whenever the door is opened. The

fingers 8 and 16 are contained in a brake-controlling circuit which serves to automatically adjust the force of the brakes with respect to the load carried on the car, such adjustment being effected when the train is stopped and the doors are opened. This brake circuit need not be further described, since it is already known to the art and constitutes no part of my invention.

What I claim as new and desire to secure by Letters Patent is:

1. A door-motor provided with a controlling valve, a magnet for operating said valve, a controlling circuit therefor, a circuit-closer for said circuit, and a retaining circuit for said valve controlled by the motor at the ends of its stroke.

2. A door-motor provided with a controlling valve, a magnet for operating said valve, and a retaining circuit for said magnet which is both closed and opened by the motor.

3. A door-motor provided with a controlling valve, a magnet for operating said valve, a starting circuit-closer for said magnet, a retaining circuit shunting said circuit-closer, and contacts in said retaining circuit operated by the motor.

4. A door-motor provided with a controlling valve, a magnet for operating said valve, a starting circuit-closer for said magnet, a retaining circuit for said valve, a contact strip in said retaining circuit of a length substantially equal to the length of stroke of the motor, and contacts cooperating with said strip to hold said retaining circuit closed during the travel of the motor.

5. A door-motor provided with a movable piston and a controlling valve, rotatable contacts actuated by said piston, a magnet for operating the controlling valve, a starting switch for said magnet and a retaining circuit for the valve controlled by the said rotatable contacts.

6. A door-motor provided with a movable piston, a rotatable contact-drum operated by said piston, a controlling-valve for said motor, a magnet for said valve, and a retaining-circuit for said valve controlled by the contacts on said drum.

7. A door-motor provided with a controlling valve, a magnet for operating said valve, a starting circuit-closer for said magnet, a retaining circuit for the magnet, and means for controlling said retaining circuit by the motor comprising a rotary-contact provided with a cam surface and a dead-centered switch-contact operated by said cam.

In witness whereof I have hereunto set my hand, this 16th day of July, 1915.

THOMAS FARMER, JR.
